R. S. ASPINWALL,
COMBINED SOCKET COVER AND LAMP RING LIGHT FIXTURE,
APPLICATION FILED MAR. 30, 1921.

1,412,644.

Patented Apr. 11, 1922.

Robert Sayer Aspinwall INVENTOR.

BY

Ralph J. Banton ATTORNEY.

UNITED STATES PATENT OFFICE.

ROBERT SAYER ASPINWALL, OF DETROIT, MICHIGAN.

COMBINED SOCKET-COVER AND LAMP-RING LIGHT FIXTURE.

1,412,644.

Specification of Letters Patent. Patented Apr. 11, 1922.

Application filed March 30, 1921. Serial No. 456,965.

To all whom it may concern:

Be it known that I, ROBERT SAYER ASPINWALL, a citizen of the United States, residing at Detroit, in the county of Wayne and State of Michigan, have invented a certain new and useful Improvement in a Combined Socket-Cover and Lamp-Ring Light Fixture, of which the following is a specification.

My invention relates to a combined socket 10 cover and lamp ring, and means for securing said ring in position over the mouth of said socket cover.

The object of my invention is to provide a simple, inexpensive, easily adjustable combination of a socket cover and lamp ring which presents a pleasing appearance, and which is so constructed that the lamp ring can be easily and quickly engaged and disengaged from the socket cover.

20 A further object is to provide a socket cover and lamp ring adapted to be secured thereto, in which the securing means carried by the socket cover, is of such a character that it may be quickly expanded to the desired radius to engage the lamp ring.

These and other objects of the invention together with details of construction will more fully appear from the following description, appended claims, and accompanying drawings, in which:

Fig. 1 is an elevation of my combined socket cover and lamp ring assembled, showing a light bulb in position.

Fig. 2 is a vertical section through my assembled socket cover and lamp ring, showing means for securing the lamp ring in position over the mouth of the socket cover.

Fig. 3 is a plan of my assembled device.

In the drawings, let *a* indicate a socket 40 cover of any conventional form, cut away at *b* to provide an opening for the switch button *c*. This socket cover is adapted to be received over a light socket; and near the mouth thereof, and circumferentially arranged therearound, is a series of outwardly extending supporting arms, here shown in the form of screws *d* threaded in the wall of the socket cover; three being here shown, extending outwardly, radially, therefrom, capable of adjustment to vary the radius thereof.

The lamp ring is indicated as *e*. It is provided with an axial opening through which the neck of the light bulb *g* passes, and the 55 edge of the lamp ring is rolled over as at *f* so

as to engage over the ends of the screws *d* to secure the lamp ring over the mouth of the socket cover.

The socket cover retains the lamp ring in position over the mouth thereof by means of the screws engaging underneath the turned over edge of the ring. To permit the easy and quick engagement and disengagement of the lamp ring over the mouth of the socket cover, I provide a notch *h* cut in the turned over portion of the lamp ring. This notch *h* is of such size as to permit the passage of a screw *d* therethrough, and is cut to such a depth as to establish a radius greater than that established by the edge of the turned over portion of the ring.

In the assembly of this device, the mouth of the socket cover is inserted within the ring, two of the screws being inserted underneath the turned over portion of the ring, 75 and the other screw passed through the notch *h*. The socket cover is then rotated relative the ring as shown in Fig. 3, and the device is securely assembled together.

In the construction I have here shown, no adjustment of the screws after the ring has been received over the socket cover is necessary. The screws can be adjusted to the desired radius before the ring is passed over the mouth of the socket cover. The assembly of the device is easy and quickly accomplished. It is apparent that if it were not desired to roll over the edge of the ring, an annular groove might be formed therein near the edge thereof to serve the purpose 80 of the present bulge formed by rolling over the edge.

In the embodiment of my invention, here shown, I show the lamp ring as carried by a conventional form of socket cover; however, 95 it is apparent that the combination might exist between a lamp ring and a separate device, similar to a socket cover, such as a band adapted to engage a socket, such band provided with outwardly projecting arms. 100 The invention lies in the means for securing the lamp ring to the annular member it encircles.

What I claim is:

1. In a device of the class described, in combination, a socket cover, a lamp ring provided with a rolled over edge, said lamp ring adapted to be received over the mouth of the socket cover, radial extensions arranged circumferentially about said socket 110

20 **BEST AVAILABLE COPY** *L. S. Aspinwall*

cover adapted to be received under the rolled over edge of the lamp ring and adapted to hold the same in position on the socket cover, and an opening in the rolled over portion of the lamp ring sufficient to permit the passage of one of the extensions of the socket cover therethrough.

2. In a device of the class described, in combination, a socket cover, a lamp ring provided with a turned over edge, said lamp ring adapted to be received over the mouth of said socket cover, and socket cover provided with a series of circumferentially arranged outwardly extending arms of a radius greater than the radius of the edge of the turned over portion of the lamp ring, said turned over portion of the lamp ring notched to provide an opening of such size as to permit the passage of one of the arms of the socket cover therethrough.

3. In combination with a socket cover provided with a series of outwardly extending lugs positioned near the mouth thereof, a lamp ring adapted to be received over such mouth of the socket cover, said lamp ring being provided with an annular groove within which the outwardly extending lugs of the socket cover are adapted to engage so as to secure the ring on the said cover, the

wall of said ring cut away to form a notch 30 into the groove of sufficient size to permit one of the lugs passing therethrough.

4. In a device of the class described, in combination, a socket cover, supporting members threaded into the wall near the mouth 35 thereof and adapted to extend outwardly therefrom, a lamp ring adapted to be received over the mouth of the socket cover, said lamp ring provided with an annular bulge near its outer edge adapted to engage 40 over the ends of the supporting members carried by the socket cover so as to secure the ring thereto, the annular bulge of said ring notched to permit the passage of a supporting arm therethrough in the engagement 45 and disengagement of the ring and the socket cover.

5. In a light fixture, in combination, an annular member provided with outwardly extending arms, a lamp ring provided with 50 a circumferential groove adapted to encircle said annular member the ends of the arms being engaged in the groove of the ring, an opening in the wall of the ring into the 55 groove thereof of sufficient size to permit the passage of an arm therethrough.

ROBERT SAYER ASPINWALL.
